CLAIM

The ornamental design for a filtered face mask, as shown and described.

DESCRIPTION

The present application claims the benefit of provisional patent application 63/102,253 to Soma et al., titled: "Tactical Armed Forces Filtering Face Mask," filed Jun. 5, 2020 which is incorporated herein by reference.

The present application is also related to co-pending utility application Ser. No. 16/873,908 titled "Filtered Face Mask" filed the same day.

The present application is additionally related to co-pending design patent application Ser. Nos. 29/742,298 and 29/742,295 titled: "Filtered Face Mask Respirator" and "Filtered Face Mask Respirator With Cap" both filed on the same day as the present application.

The present application is also related to co-pending design application for "Filtered Face Mask with Cap" application Ser. No. 29/742,296 filed the same day.

The invention described herein may be manufactured and used by or for the Government of the United States of America for governmental purposes without the payment of any royalties thereon or therefor.

FIG. 1 is an isometric top, right, front view of a filtered face mask in accordance with the invention;

FIG. 2 is an isometric bottom rear left view thereof;

FIG. 3 is a front view of the embodiment of FIG. 1;

FIG. 4 is a right side view of the embodiment of FIG. 1;

FIG. 5 is a rear view of the embodiment of FIG. 1;

FIG. 6 is a left side view of the embodiment of FIG. 1;

FIG. 7 is a top view of the embodiment of FIG. 1;

FIG. 8 is a bottom view of the embodiment of FIG. 1;

FIG. 9 is a first cross sectional view of FIG. 1 taken at the section line 9-9 of FIG. 3; and,

FIG. 10 is a second cross sectional view of FIG. 1 taken at the section line 10-10 of FIG. 3.

(Continued)

The ornamental design for a filtered face mask according to the invention is shown in the drawings, and the dashed lines shown in the drawings form no part of the claimed design.
